CLAIM

The ornamental design for a golf bag with stand, as shown and described.

DESCRIPTION

FIG. 1 is a front elevational view of the golf bag with stand showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view;

FIG. 7 is a perspective view, with the legs extended; and,

FIG. 8 is a perspective view, with the legs retracted.

Note being taken that the alphanumeric designations in the various figures are for illustrative purposes only and form no part of the invention.
